UNITED STATES PATENT OFFICE.

HENRY SCHMITT, OF DETROIT, MICHIGAN.

MOTOR BOAT.

Application filed March 14, 1927. Serial No. 175,155.

This invention relates to a boat construction and particularly to motor boats of the small or pleasure type. An object of the invention is, by the construction, to increase 5 the speed and at the same time provide a small light craft which is seaworthy and cheap to manufacture. A further object is to utilize the lifting power of air to raise the craft so that when traveling at high 10 speeds, only a small portion thereof will be in the water, and to confine the air so utilized to a certain path or stream, thereby increasing its lift. It is also an object to utilize a portion of the boat deck as an air- 15 plane and as a connection between a plurality of hulls, and to utilize such hulls as engine pits for the housing of engines. It is a further object to provide a very simple construction affording great strength and 20 providing a boat of high speed which is non-capsizable and which embodies other new and useful features, all as hereinafter set forth.

With the above and other ends in view, 25 the invention consists in the matters herein-after set forth and more particularly pointed out in the appended claims, reference being had to the accompanying drawing in which

Figure 1 is a plan view of a boat illustrative of an embodiment of the present invention;

Fig. 2 is a central longitudinal section through the same;

Fig. 3 is a transverse section substantially 35 upon the line 3^x of Fig. 1, and

Fig. 4 is a similar cross section on the line 4^x of Fig. 1.

The present construction embodies a plurality of long narrow hulls indicated as a 40 whole by the numeral 1 and a deck 2 which spans the hulls and forms a rigid connection therebetween, said hulls being spaced apart to provide an air passage 3 between the hulls and beneath the deck. This deck 45 between the hulls is planked or covered to provide a smooth under surface 4 which surface serves as an air-plane between the hulls which will act, when the boat is traveling at comparatively high speed, as a lifting plane to receive the impact of the air and tend to raise the entire boat. This lifting effect is further increased by confining the air between the adjacent hulls and also by 50 preferably inclining the deck downwardly from stem to stern of the boat. As shown this inclination of the deck may be as shown,

with its rear end extending downwardly to approximately the normal water line of the boat, but when in action, the boat will be lifted by the lifting action of this plane so 60 that the rear end of the deck or plane will be above or adjacent the surface of the water. A longitudinal air passage is thus formed between the two hulls with this passage open at its fore and aft ends, thus confining the air stream laterally, but permitting its escape at the stern of the boat. High lifting power is therefore secured.

Obviously the fore and aft inclination of the plane may be varied as desired to suit 70 the size and speed of the boat and it may be found desirable to so incline this plane that the aft end of the inclined portion will be some distance forwardly of the stern of the boat and may extend downwardly to near 75 the plane of the keels of the hull. Where the inclined plane extends at its aft end to a plane below the surface of the water, the air will be more or less trapped in the passage between the hulls but will raise the 80 boat stern and compress the water at the stern sufficiently to allow this air stream to escape. The boat will thus ride largely on air, and the speed will be increased thereby.

As shown, the two hulls are each formed 85 with substantially vertical sides formed by two spaced apart planks 5 extending from bow to stern and curved toward each other to form the pointed bow. These planks thus in effect form longitudinal sills or members 90 upon which the engines 6 are supported within the engine pits 7 in the hulls, and the bottom of each hull is formed by planking 8 secured to these sills, thus forming substantially flat bottoms for the two hulls. Side 95 planking 9 extends outwardly and upwardly from the sill 5 at the outer side of each hull, and similar planking 10 forms the inner side of each hull above the sill 5, joining at its upper edge, the 100 lower surface 4 of the deck which deck is supported upon a series of transverse girders 11 which span the space between the hulls and are secured to the sides 9 and 10 of the hulls except at the pits 7 and cock 105 pits 12 at the stern of the hulls where these girders 11 are cut short and span the space between the hulls only, being secured at their ends to the inner walls 10 and members 5 to leave the pits open. A deck planking 110 13 is laid upon the girders 11 throughout the length of the boat except over the

pits, and thus the two hulls are connected by a deck structure which is very rigid due to the deck girders extending across both hulls and from side to side of the boat. The sides 5 of the hulls may be extended upwardly past the sides of the deck to form side rails 14 if desired but due to the inclination of the deck, said deck will be substantially flush with the top of the rails at the bow of 10 the boat. A transverse wall or rail 15 connects the side rails at the stern above the plane of the deck and also closes the stern of each hull.

Directly forward of each engine pit 7, a 15 tube 16 extends vertically downward through the deck and through each hull, opening through the bottoms 8 thereof to conduct away any water that may run down on the deck toward these pits and to provide air 20 vents opening through the flat bottoms of the hulls to break the slight vacuum formed beneath the flat bottoms of the hulls as the boat travels forward at high speed. Each tube 16 has a flange 17 at the rear side of its 25 upper open end to stop the flow of water down the deck and deflect it into said tubes.

Obviously, changes in construction other than those previously mentioned, may be made within the scope of the appended 30 claims, without departing from the spirit of the invention, and I do not therefore limit myself to the particular construction shown.

What I claim is:—

- 35 1. A boat including a plurality of hulls and a rearwardly and downwardly inclined deck for said hulls rigidly connecting the same and having an under smooth surface forming an air-plane between said hulls when the boat is proceeding forwardly.
- 40 2. A boat including a plurality of spaced apart hulls, means rigidly connecting said hulls and spanning the space there-between said means providing a smooth lower surface inclined downwardly from bow to stern

and with said surface above the water line 45 of the hulls and forming the top of the air passage between the hulls with said passage open at bow and stern when the boat is being driven forwardly.

3. A boat including a pair of spaced apart 50 hulls, and a deck extending across said hulls and spanning the space between the hulls, the underside of said deck between said hulls being smooth and inclined rearwardly and downwardly with a space between the 55 rear end thereof and the surface of the water when the boat is running forwardly.

4. A boat including a pair of spaced apart 60 hulls having substantially, longitudinally straight adjacent sides forming an air passage therebetween open at bow and stern, and means rigidly connecting said hulls, and closing the upper side of said air passage, said means having a smooth under surface inclined rearwardly and downwardly with a 65 space between the rear end thereof and the surface of the water when the boat is running.

5. A power boat including a pair of hulls, each affording an engine pit, a deck rigidly 70 connecting said hulls and extending across and closing said hulls and spanning the space therebetween, said deck having a smooth under surface between said hulls and inclined from bow to stern with a space between the stern of said surface and the water 75 surface when the boat is running.

6. A power boat including a pair of hulls spaced apart and having substantially 80 straight parallel sides, and a deck extending across both hulls and across said space, said deck extending from bow to stern of the boat and inclined from the bow downwardly toward the stern to above the water line 85 of the boat when in forward motion.

In testimony whereof I affix my signature.

HENRY SCHMITT.
